UNITED STATES PATENT OFFICE.

EMIL CAPITAINE, OF FRANKFORT-ON-THE-MAIN, GERMANY, ASSIGNOR TO
GEORGE T. HARRIS, OF PHILADELPHIA, PENNSYLVANIA.

VAPORIZER AND COMBUSTION-CHAMBER FOR PETROLEUM-MOTORS.

SPECIFICATION forming part of Letters Patent No. 581,412, dated April 27, 1897.

Application filed May 22, 1896. Serial No. 592,592. (No model.)

To all whom it may concern:

Be it known that I, EMIL CAPITAINE, a citizen of the German Empire, and a resident of Frankfort-on-the-Main, Germany, have invented and produced a new and original Vaporizer and Combustion-Chamber for Petroleum-Motors, of which the following is a specification, reference being had to the accompanying drawings, forming a part thereof.

10 My invention relates to petroleum-engines; and it consists principally in constructing the combustion-chamber with passages in its walls, which passages emanate from a common passage-way within the same into which air and petroleum are respectively delivered through separate inlet-ports, both governed by a single valve, whereby an intimate mixing of petroleum-vapor and of air takes place before the former can come in contact with 15 the cooled surfaces of the power-cylinder and before the charge of vapor and air is delivered into the combustion-chamber.

15 In the accompanying drawings, illustrating my invention, Figure 1 is a vertical section with the discharge-valve, actuating devices shown in elevation, and Fig. 2 is a horizontal section through the lines 1 2 of Fig. 1.

20 The power-cylinder is indicated at A and is provided with passages a in its walls to enable it to be cooled in any proper and known manner.

25 B is the power-piston, and E the usual valve thereof.

30 Mounted above the power-cylinder and opening into the same is the non-cooled combustion-chamber C, the top of which is provided with a discharge-port d, valve d' having stem D for discharging the products of combustion, the said valve being actuated by 35 any proper means, such as indicated in the drawings at F. The combustion-chamber at its top is constructed as shown in Fig. 2—that is to say, its walls have two internal passage-ways c² c², terminating in ports c' c', opening 40 into the chamber, and these passage-ways c² c² emanate from a single and common passage-way c, the entrance to which is governed by a spring-controlled check-valve b, which likewise and by the same movements controls the 45 inlet-ports b' b² for admitting the requisite

quantity of petroleum-vapor and air, respectively.

The chamber c, above referred to, is formed in a lateral extension (see Fig. 2) of the combustion-chamber, into which the inlet-ports 55 extend, and the passage-ways c² extend out through the walls of this extension.

The general principle of construction and mode of operation other than as stated of this petroleum-motor are the same as in other 60 known gas-engines having four movements of the piston to each revolution.

The operation of the device as improved by my novel construction of the combustion-chamber and vaporizer C is as follows: During 65 the suction-stroke of the power-piston B, following the upstroke, which has discharged the burned products of the previous explosion through the valve-port d' and discharge-port d, the spring-controlled valve E will rise and 70 open its port, admitting air, while at the same time the spring-controlled check-valve b will open the air and petroleum inlet ports b' and b², admitting the requisite quantity and relatively proper proportions of air and vapor into 75 the common passage-way or chamber c and thence through the passages c² c² and ports c' c' into the vaporizer and combustion-chamber C, they having been thoroughly and intimately 80 mixed on their passage to the chamber C, which being a non-cooled chamber causes an expansion of the mixture followed by an explosion produced by the usual means, and hence there is a consequent return or drive stroke of the power-piston.

Having thus described my invention, what I claim as new, and desire to secure by Letters Patent, is—

The combination of the power-cylinder, the non-cooled combustion-chamber opening into 90 said power-cylinder, and having its wall or shell formed with a lateral extension, a supplemental chamber formed in said extension, air and vapor inlet ports leading into said supplemental chamber, and internal passages 95 c² c², emanating from said supplemental chamber and extending through said extension into the wall of the combustion-chamber and terminating in ports which communicate with the upper portion of said combustion-cham- 100

ber, together with a valve seated in said supplemental chamber and arranged to control communication between the inlet-ports and the said passage-ways, and a spring for controlling the movement of said valve, substantially as specified.

In testimony whereof I have signed my

name to this specification in the presence of two subscribing witnesses.

EMIL CAPITAINE.
